THREAD GUIDING DEVICE

William R. Schmitz, Jr., Newark, N. J.

Application July 9, 1949, Serial No. 103,888

7 Claims. (Cl. 28—71.5)

1

The present invention relates to an improved thread guiding device by means of which the stringing-up of a plurality of spaced reels with filaments or threads may be accomplished.

An object of the invention is to provide a thread guiding device wherein the aforementioned stringing-up operation may be accomplished effectively and, in addition, wherein the wrapping of the thread or filament about the various reels is prevented during operation thereof.

In the manufacture of endless threads or filaments, such as artificial silk, the threads have heretofore been guided over spaced reels for storing during various treating operations that are performed upon the threads. In the operation of these devices it has been difficult to string-up the thread upon the rolls at the beginning of an operation or after a filament has been broken. A further serious difficulty encountered in these mechanisms has been the tendency of the filament to wrap around the reels and require careful and prompt attention in order to restore the mechanism to operating condition.

A device according to the present invention may comprise two or more spaced and rotatable reel members and an endless transfer belt trained around said reel members for guiding the leading end of a thread from the periphery of one reel member to the periphery of another reel member in such a manner that the thread path defined by the reel members is generally in the form of a spiral.

The term "spaced," as applied to the reel members in the description of this invention, is intended to mean that the peripheries of the two or more reel members associated in a unit of the thread store device are disposed wholly outside one another.

In one preferred embodiment of the invention, two or more cylindrical reel members are associated in a thread guiding unit, and the transfer belt trained around the two or more reel members comprises a pair of spaced and flexible and/or elastic band or chain members and a plurality of transverse rung members secured at each end to a band or chain member, the rung members being loosely engageable in the longitudinal grooves of the reel members to lie below the peripheral surfaces thereon and to adjust themselves to the angular relation between the axes of rotation of the reel members.

In another embodiment, the transfer belt trained around the reel members comprises a plurality of rung members wherein both ends of each rung member are suitably shaped in the form of forwardly extending hooks or eyes engaging the ends of an adjacent rung member.

In still another preferred embodiment, the transfer belt comprises a single sprocket or roller chain, equidistantly spaced pins of which are ex-

2

tended transversely of the chain for loose engagement with the grooves in the reel members.

The device of this invention is useful in a process of making or treating endless threads or filaments, such as artificial silk, and is particularly applicable to the manufacture and treatment of artificial silk made by the viscose process. Thus, for example, several thread guiding units, each comprising an association of two or more reel members and a transfer belt trained there-around, may be utilized to subject spun fibers to successive storing, washing, desulfurizing, drying and other treatments. If desired, one or more of the reel members in any given unit may be partly or wholly immersed in a liquid.

One of the outstanding advantages of a device embodying the principles of this invention is that a thread need not be threaded manually around the device. The wet leading end of a thread need simply be placed on the reel or belt, whereupon it is picked up by a rung member of the transfer belt, deposited on the peripheral surface of another reel member, picked up again by a rung member of the belt and, at the end of one cycle, carried back to the first reel member to be deposited on the periphery thereof at a point closer to the far end of the reel member. Continued rotation of the reel member results in repetitions of this cycle until the leading end of the thread reaches the far end of one of the reel members, whereupon it is advanced to another thread store device for further treatment, and finally to a wind-up reel or the like.

This and other advantages, as well as the utility and objects of the invention will become more apparent from the detailed description of several preferred embodiments of the device illustrated by way of example only in the accompanying drawing wherein:

40 Figure 1 is a view in elevation of one preferred embodiment of the invention;

Figure 2 is an end view in elevation of the device illustrated in Figure 1;

Figure 3 is a view in section taken along section line 3—3 of Figure 2;

Figure 4 is a view in section taken along section line 4—4 of Figure 1;

Figure 5 is a detailed partial view in section taken along section line 5—5 of Figure 3;

50 Figure 6 is a view in elevation of another embodiment of the invention;

Figure 7 is an end view of the embodiment illustrated in Figure 6; and

Figure 8 is a view in elevation of a further embodiment of the transfer belt construction.

In the embodiment illustrated in Figures 1 to 5, inclusive, a pair of cylindrical reel members 10 and 11 are mounted for rotation at one or both ends to a supporting frame member 12. The reel member 10 is fixed to a shaft 14 journaled in

bearing 16 and provided with a driven gear or pulley 17. The other reel member 11 is mounted on a shaft 19 supported at an angle to the shaft 14 in a bearing 20 which may, if desired, be adjustably secured to the frame member 12 by means of stud bolts 21 slidable laterally in slots 22.

Reel members 10 and 11 are provided with a plurality of longitudinal flutes or grooves 24 spaced around their peripheries. These grooves 24 preferably have an addendum with the contour of a sprocket tooth and a dedendum with the contour of a spur gear tooth. A transfer belt 26, consisting of a plurality of spaced rung members 27 extending across the belt and maintained in spaced relation to one another by a pair of flexible and/or elastic band members 29, is trained around the reel members 10 and 11.

The spacing of the flutes or grooves 24 on the peripheries of the reel members 10 and 11 and of the rung members 27 is such that the rung members will engage with the grooves. The depth, and width at the bottom, of the grooves 24 are such, in relation to the diameter of the rung members 27, that the rung members will lie loosely in the grooves below the exposed peripheral surfaces 30 of the reel members 10 and 11 and have sufficient clearance to permit longitudinal adjustment of their positions within the grooves to compensate for the angle between the axes of rotation of the two reel members.

In operation, the thread guiding device, illustrated in Figures 1 to 5, is actuated by rotating shaft 14 by any suitable means. The wet leading end of a thread is fed onto the reel member 10 at A. The end adheres alternately to one of the reel members 10 and 11 and to a rung member 27 and is, by reason of the adjustments of the position of the rung member 27 within the grooves to compensate for the angle between the axes of the reel members, advanced spirally around the reel members 10 and 11 and over the rung members 27 of the conveyor belt 26 until it is withdrawn at B for further processing. The tension of the transfer belt 26 can readily be adjusted by loosening stud bolts 21 and moving the bearing 20 for the shaft 19 toward or away from the shaft 14 and then tightening the stud bolts 21.

Referring to the modifications shown in Figures 6 and 7, reels 31 and 32 correspond to reels 10 and 11 of the form of the invention shown in Figures 1 to 5. A transfer belt 33 which may, if desired, be in the form of an endless chain, is threaded over the reels, the reels being provided with grooves 24 similar to those formed in reels 10 and 11. The transfer belt 33 is formed with rungs 34 corresponding to the rung members 27 in the form of the device shown in Figures 1 to 5, such rungs being received in the aforesaid grooves 24. It will be observed that the axes of the reels 31 and 32 lie in horizontal planes that are parallel to each other, but that the axes are askew and lie in different vertical planes which intersect. This will be readily apparent from Figure 7. The feeding of the thread or filament onto the rolls is accomplished in a manner similar to that described in connection with the operation of the invention shown in Figures 1 to 5.

Yet another form of utilizing the present invention is illustrated in Figure 8 wherein two reel members 35 and 36 are provided, being suitably journaled in a supporting mechanism that is not shown. These reel members are shown as being mounted in the same vertical plane, but the axes thereof are askew inasmuch as the axis of the

upper reel 35 at the right-hand end thereof is spaced farther from the axis of the lower reel 36 at its right-hand end than the corresponding axes are spaced at the left-hand ends of the reels. In this fashion a thread or filament that is passed around both reels will gradually advance toward the left-hand ends of the reels as the reels rotate in unison. In order that the device may be made self-stringing in accordance with the present invention, an endless conveyor belt, shown generally at 37, is provided. This belt may be formed of an endless chain 38 which may be mounted over sprockets carried by the shafts 39 and 40 of the respective reels 35 and 36. Certain of the links of the chain 38 are provided with rungs 41 which project toward the left as viewed in Figure 8, and these rungs may be received within partial grooves formed in the reels 35 and 36, if desired. On the other hand, if preferred, the reels 35 and 36 may be entirely plain, and the conveyor mechanism with the rungs thereof may be adapted to pass over the peripheral surfaces of the reels.

In operation, the device of Figure 8 functions as a self-stringing device and wrap-preventing device during the self-stringing operation. For example, a thread or filament is applied to the rung or rungs of the conveyor 37, and a band of a filament is permitted to form or build up thereon. If the thread is then lapped back over itself, i. e., if the free leading end is held, a slack part of the thread is dropped on the reel and the free end is then moved toward the right-hand end of the reel member so that it is lapped over the thread thereon, the band is advanced beyond the ends of the rungs 41 and upon the reels 35 and 36. At this point the band progresses outwardly to the left and is followed by the continuous thread or filament which forms a spiral path between and over the reels 35 and 36. After the band leaves the rungs 41, the device is no longer wrap-preventing, but while the band is being formed and while it is upon the conveyor belt, the device is wrap-preventing.

It is to be understood that the use of the term "thread" or "filament" in this specification is merely descriptive of material that may be treated appropriately on the device and includes not only single and multiple filaments, but also bands, ribbons, cords, tow and rope. It is not intended as a word of limitation, and the invention is not to be limited save as defined in the appended claims.

I claim:

1. Thread guiding mechanism comprising at least two supporting members at least one of which is rotatable, said rotatable member being formed with a plurality of grooves, means to mount said members in spaced relationship with their axes non-parallel, means to rotate the rotatable member, an endless thread transfer mechanism mounted over the members, and driven by the rotatable member, and a plurality of spaced elements on the endless transfer mechanism to guide thread between the members, said spaced elements being received in the grooves in the rotatable member.

2. Thread guiding mechanism comprising at least two supporting members at least one of which is rotatable, said rotatable member being formed with a plurality of longitudinal grooves, means to mount said members in spaced relationship with their axes non-parallel, means to rotate the rotatable member, an endless thread transfer mechanism mounted over the members,

and driven by the rotatable member, and a plurality of spaced elements on the endless transfer mechanism to guide thread between the members, said spaced elements being received in the grooves in the rotatable member.

3. Thread guiding mechanism comprising at least two supporting members at least one of which is rotatable, said rotatable member being formed with a plurality of grooves, means to mount said members in spaced relationship, means to rotate the rotatable member, an endless thread transfer mechanism mounted over the members and driven by the rotatable member, and a plurality of spaced elements on the endless transfer mechanism to guide the thread between the members, said spaced elements being received in the grooves in the rotatable member and adapted to slide longitudinally therein.

4. Thread guiding mechanism comprising at least two supporting members at least one of which is rotatable, said rotatable member being formed with a plurality of grooves, means to mount said members in spaced relationship, means to rotate the rotatable member, an endless flexible thread transfer mechanism mounted over the members and driven by the rotatable member, and a plurality of spaced elements on the endless transfer mechanism to guide the thread between the members, said spaced elements being received in the grooves in the rotatable member and adapted to slide longitudinally therein.

5. Thread guiding mechanism comprising at least two supporting members at least one of which is rotatable, said rotatable member being formed with a plurality of grooves, means to mount said members in spaced relationship, means to rotate the rotatable member, an endless thread transfer mechanism mounted over the members and driven by the rotatable member, said endless thread transfer mechanism comprising spaced flexible endless members having a plurality of spaced elements therebetween

to guide the thread between the first named spaced members, said spaced elements being adapted to be received in the grooves in the rotatable member, and being adapted to slide longitudinally therein.

5 6. Thread guiding mechanism comprising at least two supporting members formed with longitudinal grooves, means to mount said members rotatably in spaced relationship with their axes non-parallel, an endless thread transfer mechanism mounted over the supporting members and comprising spaced flexible endless members having a plurality of spaced elements therebetween adapted to lie in the longitudinal grooves to guide the thread between the first named spaced members.

10 7. Thread guiding mechanism comprising at least two supporting members formed with longitudinal grooves, means to mount said members rotatably in spaced relationship with their axes non-parallel, an endless thread transfer mechanism mounted over the supporting members and comprising spaced flexible endless members having a plurality of spaced elements 15 therebetween adapted to lie in the longitudinal grooves and being of less thickness than the depth of the grooves, to guide the thread between the first named spaced members.
